LUBRICANT APPLICATOR FOR POLISHING WHEELS AND THE LIKE

Application filed October 16, 1931. Serial No. 569,132.

This invention relates to a new and improved form of oil and grease applicator, for polishing or buffing wheels.

One object of the invention is to eliminate the throwing of oil or grease when applying same to any moving surface.

Other objects will be noted from the following description and accompanying drawings, and in which:

10 Figure 1 is a front view of the applicator pivotally attached to a guard and in raised or rest position.

Fig. 2 is a similar view with the applicator in lowered or contact position.

15 Fig. 3 is a side view, enlarged, with the applicator partly in section.

Fig. 4 is a side elevation of the applicator, with the guard in section and the rest position and contact position both being shown.

20 Fig. 5 is an enlarged front elevation of the applicator.

Fig. 6 is a view similar to Fig. 5 but of a modified form, embodying a spray system.

25 Fig. 7 is a view similar to Fig. 3 but of the modified form.

Fig. 8 is a perspective view of the spraying device.

Fig. 9 is a rear elevation of the modified form.

30 Referring to the drawings, a hanger, consisting of a pair of arms 10 and 11, cross bars 12 and 13 and stop bar 14, is pivotally attached to a guard 15 mounted over a polishing wheel 16 on a shaft 17, said hanger pivots at 18 to allow the applicator to swing downward to contact with the polishing wheel 16, the stop bar 14 then resting on the top surface of the guard 15.

The applicator shell or casing 19, with 40 channel forming flange 20 and to the upper edge of which is attached a flexible bracket 21 with inset brushes 22, is attached to the hanger by the cross bars 12 and 13 mounted through sleeves 23 and 24 respectively, and 45 said sleeves may be mounted on the outer surface of the applicator shell 19 by suitable means such as riveting. The brush wipes the surface of the wheel 28.

Bolted to the applicator shell 19 is a handle 50 25 mounted slightly to the rear of the sleeve

23, while just forward of the sleeve 24 is attached a container 26, the spout 27 being attached in such manner as to form a fixed part of the applicator shell 19. The container 26 can be filled with oil or grease and turned 55 into the screw top of the spout 27, thus as the hanger and applicator are drawn forward and swung downward to the contacting position the oil or grease feeds to the buffing or applying wheel 28 which in turn lubricates 60 the polishing wheel 16.

The buffing wheel 28 is mounted on a shaft 29, and at each end of said buffing wheel there is a washer and link 31 held in position on the shaft 29 by a cotter pin 32. Hooked 65 through the head of the cotter pin 32 is a spring 33 the other end of the spring being anchored to the lug 34 on the inside surface of the applicator shell 19.

The springs 33 hold the buffing wheel 28 70 down against the spout 27 when the applicator is not in use, but when the buffing wheel is in contact with the polishing wheel 16 the lever arm 31 pivots on pins 34 mounted through the walls of the applicator shell 19 75 and thus carries the buffing wheel 28 upward with the pressure.

Buffer springs 36 are attached to the inner surface of the applicator shell 19 to prevent the shifting of the buffer wheel 28. 80

This apparatus may be used as a hand applicator by removing the hanger and grasping the container and applying in the manner that the present grease stick is used.

In the modification shown in Figs. 6 to 9 85 inclusive, a spraying device is used in place of the container. The sprayer 40 has a flat surface 41 with a depression 42 having a plurality of apertures 43 slightly to one side of the middle of the said depression. The sprayer 40 is bolted to the inner surface of the applicator shell 19a and with the apertures 43 on the lower side. Between the sprayer and the applicator shell is a gasket of cork or the like, said gasket 44 partaking of the shape of 90 the flat surface of the sprayer; bolts 45 holding both sprayer 40 and gasket 44 in position over the aperture 46 in the threaded stem 47 which is an integral part of the applicator shell 19a. 95

Screwed on the threaded stem 47, outside of the applicator shell, is a screw connection 48 with a tapered tubular end 49 to which a hose may be attached through which the oil or grease may be fed by pressure, to the sprayer 40 and thus through the apertures 43 to the buffing wheel. The use is similar to that above described.

We claim:

- 10 1. A lubricant applicator for polishing wheels comprising a shell pivotally mounted over the wheel, a lubricant bottle carried by the shell and arranged to be tilted therewith to either upright or inverted position, and an applying wheel mounted in the shell and movable therewith to contact with the polishing wheel, said applying wheel being in position to receive lubricant from the bottle when in contact with the polishing wheel.
- 15 2. A lubricator applicator as in claim 1, and a wiper carried by the shell and bearing against the applying wheel.

3. The combination with a polishing wheel and its guard, of a lubricant applicator pivotally mounted on the guard and comprising a shell pivoted to the guard above the wheel, an applying wheel mounted in the shell and movable therewith into and out of contact with the polishing wheel, and means to supply lubricant to the applying wheel, said means including a nozzle fixed in the shell and an oil receptacle attached to the nozzle and arranged to swing with the shell to either upright or inclined position.

4. A lubricant applicator as in claim 1, the mounting for the applying wheel including a pair of links pivoted to the shell, and springs between the links and the shell permitting yielding movement of the applying wheel.

JOHN H. KEATING.
